(57) **CLAIM**

The ornamental design for the prefabricated building part, as shown and described.

DESCRIPTION

FIG. 1 is a perspective view of a prefabricated building part, of my new design;

FIG. 2 is a front elevational view thereof;

FIG. 3 is a right side elevational view thereof;

FIG. 4 is a rear elevational view thereof;

FIG. 5 is a left side elevational view thereof; and,

FIG. 6 is a top plan view thereof.

The prefabricated building part of my new design has a bottom that is flat and devoid of surface ornamentation.
